E. CURRIE.
CARBURETER ATTACHMENT.
APPLICATION FILED AUG. 12, 1918.

Patented Mar. 18, 1919.

UNITED STATES PATENT OFFICE.

EMERSON CURRIE, OF PALO ALTO, CALIFORNIA, ASSIGNOR OF ONE-HALF TO WALTER C. HONEA, OF LOS ANGELES, CALIFORNIA.

CARBURETER ATTACHMENT.

1,247,662.

Specification of Letters Patent. Patented Mar. 18, 1919.

Application filed August 12, 1918. Serial No. 249,339.

To all whom it may concern:

Be it known that I, EMERSON CURRIE, a citizen of the United States, residing at Palo Alto, in the county of Santa Clara and State of California, have invented new and useful Improvements in Carbureter Attachments, of which the following is a specification.

This invention relates to an improvement in devices automatically actuated with the advance of the ignition spark, for admitting heated gaseous fluid, such as air or gasoline vapor, into the inlet manifold of an internal combustion engine. The object of the invention is to provide means for this purpose which will be simple and inexpensive in construction and will additionally serve to thoroughly mix the air and gasoline vapor flowing from the carbureter to said manifold, and also thoroughly mix said admitted fluid with the combustible mixture of air and gasoline vapor.

The invention is primarily intended for use with an internal combustion engine of an automobile and is particularly adapted for use with a Ford car.

In the accompanying drawing, Figure 1 is a broken front view showing the invention applied to a Ford car; Fig. 2 is a broken top view thereof; Fig. 3 is an enlarged detail side view of a combined valve casing and mixer; Fig. 4 is a longitudinal sectional view of the same; Fig. 5 is a transverse sectional view of the same.

Referring to the drawing, 1 indicates a spark lever of a Ford car, operating a shaft 2, extending down by a side of the steering post 3, as in the usual construction. To a lower portion of said shaft 2 is secured, by a bolt 4, a band 5, formed of an end of a twisted strap 6, the other end of which is apertured and is engaged by a hooked end 7 of a wire rod 8. When the invention is applied to a Ford car, said rod 8 extends through the opening 9 between the front and rear pairs of cylinders of the engine. The other end of said rod 8 is bent to form a hook 10 which engages a small hole 11 through the outer end of a cylindrical slide valve 12. Cotter pins 13 are passed through holes in the ends of the rod 8 and secure said rod in its operative position. Said valve 12 can slide in a cylindrical recess 14 extending inwardly from the periphery of a valve casing or plate 15, which is interposed in

the juncture between the outlet conduit from the carbureter 16 of the engine and the adjacent end of the inlet manifold 17, and is secured in its place by means of bolts 18, similar to those which are used to secure said manifold end to said conduit, said bolts extending through holes 19 in said plate and through the holes already provided for bolts in the flanges 20, 21, extending respectively from the conduit and manifold, the periphery of the plate 15 corresponding approximately in form to those of said flanges.

The central portion of said plate is apertured to permit the combustible mixture to flow from the carbureter to the manifold, and, for the purpose of more thoroughly mixing the air and gasoline vapor flowing to the manifold, I prefer to perforate said plate by a considerable number, here shown as fourteen, of small holes 22, confined to the part of the plate which is directly interposed between the adjacent ends of the manifold and of the other conduit leading from the carbureter.

A recess 23 also extends inwardly from the periphery of the valve casing or plate 15, and communicates at its inner end with the recess 14. In the outer end of said recess 23 is driven a nipple 25, and on the portion of said nipple projecting beyond the valve casing is secured the inner end of a flexible tube 24. Said tube can conduct to the valve casing, so that it can be introduced into the inlet manifold, any gaseous fluid, but I have here shown it as used to introduce air which is heated by the exhaust in the engine, and for this purpose I have shown the other terminal portion of the tube 24 as coiled around the exhaust manifold 27. It is to be understood, however, that I do not limit my invention to this construction.

Since the cylindrical slide valve 12 moves past the inner end of the recess 23, it serves to regulate the passage of the gaseous fluid from said tube 24 and recess 23 into the recess 14. It will be seen that the parts are so arranged that, when the spark is advanced in the proper direction, the slide valve 12 is withdrawn, increasing the flow of the gaseous fluid into the recess 14 and manifold, and conversely, when the spark lever is retarded, the slide valve 12 moves inwardly, and closes the inner end of the recess 24 and reduces the flow of the gaseous

fluid into the recess 14. To avoid too great a rush of the air or other gaseous fluid into the recess 14, when the spark is advanced and the valve 12 is withdrawn, the inner 5 end 28 of said valve is reduced in diameter and is also slightly tapered. The cylindrical recess 14 is bored in the plate 15 not only some distance past the inner end of the recess 23, but through those of the walls 31 10 separating from one another the small holes 22, which are in the direct line of the bore. The object of the latter construction is to form mixing chambers and facilitate the admixture of the air or other gaseous fluid introduced through the flexible tube 24 with 15 the combustible mixture from the carbureter.

For the same purpose, and also to assist in thoroughly mixing the air and gasoline 20 vapor flowing from the carbureter, a hole 30 is bored from the periphery of the plate 15 at right angles to the hole 14 and is extended through those of the walls intervening 25 between the small holes 22 which are in line with said bore. The outer portion of this hole is then filled by a stopper 32 driven tight into the plate 15.

It will now be seen that I have provided a device which may be interposed in the inlet 30 manifold of an internal combustion engine which will not only serve to regulate the admission of heated air or other gaseous fluid with the movement of the spark lever but will also contain a mixing chamber and 35 render more homogeneous the mixture of air and gasoline vapor flowing from the carbureter and also insure the thorough mixture thereof with additional heated air or other gaseous fluid.

40 I claim:—

1. In means for mixing a fluid with the combustible mixture flowing from the carbureter to the inlet manifold of an internal combustion engine and simultaneously rendering 45 said mixture more homogeneous, a plate interposed between the outlet end of the outlet conduit of the carbureter and the inlet end of the inlet conduit of the inlet manifold having therethrough a plurality of small holes adapted to register with said outlet and inlet conduits, also having therein a passage leading from its periphery and communicating with a plurality of said holes through their walls and a passage leading 50 from said periphery to said first named passage, a slide valve in said first passage to vary the size of the opening between said passages.

2. In means for mixing a fluid with the combustible mixture flowing from the carbureter to the inlet manifold of an internal combustion engine and simultaneously ren-

dering said mixture more homogeneous, a plate interposed between the outlet end of the outlet conduit of the carbureter and the 60 inlet end of the inlet conduit of the inlet manifold having therethrough a plurality of small holes adapted to register with said outlet and inlet conduits, also having therein a passage leading from its periphery and 70 communicating with a plurality of said holes through their walls and a passage leading from said periphery to said first named passage, a conduit communicating with the outer end of said latter passage for conducting fluid thereto, and a slide valve in said first passage to vary the size of the opening between said passages. 75

3. In means for mixing a fluid with the combustible mixture flowing from the carbureter to the inlet manifold of an internal combustion engine and simultaneously rendering 80 said mixture more homogeneous, a plate interposed between the outlet end of the outlet conduit of the carbureter and the inlet end of the inlet manifold having therethrough a plurality of small holes adapted to register with said outlet and inlet conduits, also having therein a passage leading from its periphery and 85 communicating with a plurality of said holes through their walls and a passage leading from said periphery to said first named passage, a slide valve in said first passage to vary the size of the opening between said 90 passages, said plate having also a passage extending transversely to said first-named passage and communicating with said small holes through their walls.

4. In means for mixing a fluid with the combustible mixture flowing from the carbureter to the inlet manifold of an internal combustion engine having an ignition spark shaft and simultaneously rendering 100 said mixture more homogeneous, a plate interposed between the outlet end of the outlet conduit of the carbureter and the inlet end of the inlet conduit of the inlet manifold having therethrough a plurality of small holes adapted to register with said outlet and inlet conduits, also having therein a passage leading from its periphery and 105 communicating with a plurality of said holes through their walls and a passage leading from said periphery to said first named passage, a slide valve in said first passage to vary the size of the opening between said 110 passages, a crank secured to the lower end of the ignition spark shaft of the engine, and a rod of which one end is connected to 115 the outer end of said crank, and the other end is connected to the outer end of said slide valve. 120

EMERSON CURRIE.
